APPARATUS FOR SHEARING

Lorenz Iversen, Pittsburgh, Pa., assignor to Mesta Machine Company, Pittsburgh, Pa., a corporation of Pennsylvania

Application November 24, 1934, Serial No. 754,607

12 Claims. (Cl. 164—68)

This invention relates to apparatus for shearing and is particularly useful in connection with the shearing of metal strip. Metal strip, especially that which is of great width, is now produced at high speed in long lengths by rolling on hot mills of the continuous type, and, when delivered from the mill, must be expeditiously handled. For purposes of after-treatment, it is sometimes desirable to cut the strip into short lengths and at other times simply to crop it (and perhaps divide a length into two or even three pieces) and form the strip into a coil or coils. The leading end of the strip is always more or less irregular and must be cropped off. This cropping, as well as the shearing of the strip into lengths, or the parting thereof into two or more long pieces adapted to be coiled, may conveniently be carried out by a shear of the rotary type. I have heretofore developed shears of this type which function very satisfactorily for such purposes. Such shears are shown, for example, in my prior Patents Numbers 1,876,456 and 1,890,221.

A problem which has become of increasing importance as mills of higher capacity have been built is the disposition of the cropped end of the strip. The strip leaves the delivery stand of the continuous mill while still at relatively high temperature and at a speed of 1400-2000 feet per minute, or more. The strip may be six feet or more in width and the cropped end is so large and unwieldy that it is difficult if not impossible in the wider widths to handle manually. This cropped end must be quickly taken out of the way of the oncoming strip so as to permit of coiling or otherwise disposing of the strip without danger of it being fouled by the presence of the cropped end. The present invention provides a means whereby this result can be readily, safely and economically accomplished. The strip is ordinarily rolled and handled while lying in a substantially horizontal plane, and I provide means for cropping the leading end of the oncoming strip and for diverting the cropped leading end out of the horizontal plane of the roll table or other support provided for the strip proper. This diverting means preferably takes the form of a vertically movable section in the roll table or other support, which, in one position, will divert the cropped end of the metal out of the general plane of the support, and in another position will permit passage of the metal thereover. It is necessary that the switching means be arranged to act with great rapidity because the strip is moving at such high speed that the time when the movement of the switch-

ing device takes place relative to the moment of shearing is of the utmost importance. Unless a proper control is effected there is great danger of fouling the strip and cobbling it. The problem is rendered difficult by the high speed at which the shearing mechanism necessarily acts. I therefore arrange for a preliminary setting of the switch member in one position, preferably in the position to divert the cropped end of the strip, and I provide constantly acting power means, as, for example, a fluid actuated cylinder, tending always to throw the switch to the other position. A trip mechanism, operatively connected with the shear, causes the switch to act at the right moment, so that the switching is accomplished smoothly and without danger of fouling.

In the accompanying drawings illustrating a present preferred embodiment of the invention,

Figure 1 is a diagrammatic view illustrating the shear, the tables, the switching mechanism, and the control apparatus;

Figure 2 is a side elevation, partly broken away, showing the shear and switching mechanism in detail;

Figure 3 is a front view, partly broken away, of the apparatus shown in Figure 2; and

Figure 4 is a horizontal section taken on the line IV—IV of Figure 3.

Referring to Figure 1, there is shown a feed mechanism, indicated generally by the reference character 2, which may be the last stand of a continuous mill, or may be some other feed mechanism, for example, a pair of pinch rolls. A strip fed from the rolls 2 passes over a roll table 3 to a rotary shear 4. The shear is effective for cropping the leading end of the strip and may also serve to part the strip into two or more pieces for coiling, or to cut it into short lengths. The material delivered from the shear is taken away by a roll table 5.

The shear, which may be of the type shown in one of my patents above referred to, comprises an upper shearing roll 6 and a lower shearing roll 7 provided with cooperating cutting blades 8. The shear is driven by a motor 9 through reducing gearing 10, and the starting and stopping of the motor 9 is preferably controlled by a flag switch 11 arranged in the roll table 3. When the shear is used for cropping, it will ordinarily be at rest with the blades 8 in such position that the strip can pass freely therebetween. But when the leading end of the oncoming strip passes over the flag switch 11, the motor 9 is started up, the control mechanism being so arranged that the shear blades have

been brought up to cutting and into shearing position at such a time as to insure a satisfactory yet economical crop.

In order to dispose of the cropped leading end 5 of the strip, there is provided a switch, which is best shown in Figure 2 and is indicated generally by the reference character 12. This switch is pivoted at 13 and is adapted to be raised and lowered about such pivot. In Figure 2 it is shown in its lowered position. The switch comprises a generally wedge-shaped body 14 made of plates welded together to form a table over which the material may pass, this body having idle supporting rollers 15 therein. 15 Openings 16 are provided in the bottom of the body to give access to the rollers 15, and the adjacent bottom wall portions 17 are turned inwardly and upwardly so as to avoid any danger of fouling the leading end of a crop when it is 20 discharged beneath the table.

As above indicated, the switch 12 is in raised position when the leading end of the strip comes between the shear rolls 6 and 7. At this time the pointed nose 18 of the switch is in the position indicated at 18-a, and hence the leading end of the strip is directed below the table 14 and into a pit, not shown, from which the collected croppings can be removed. The switch 12 may be held in raised position by a latch 30 mechanism, hereinafter described, but is constantly urged downwardly, not only, by its own weight, but also by an air cylinder under constant pressure. This construction insures that the moment the switch is tripped it will move 35 with extreme rapidity to its lowermost position, so that when the freshly cut end of the oncoming strip reaches a point adjacent the end of the switch 12 the strip will lie above the switch and will be projected over the table 14 as it issues 40 from between the shear rolls.

Near its pointed end the body 14 is provided with trunnions 19 (see Figure 3) which are connected by links 20 to arms 21 on a shaft 22. The shaft 22 is carried in bearing members 23 secured to the housing 24 of the shear. The shaft 22 also carries arms 25 to which is pivoted the piston rod 26 of a piston 27 working in a cylinder 28. The cylinder 28 is trunnioned in the members 23 as shown at 29. A flexible connection 30 (see Figure 2) supplies air under high 50 and constant pressure in the lower end of the cylinder 28, so that the shaft 22 is biased in a clockwise direction, thus tending always to force the switch 12 to its lowered position.

The latching up of the switch 12 is accomplished by a latch lever 31 on the shaft 22 co-operating with a latch 32 which is pivoted at 33. A spring 34 urges the latch into engagement with the latch lever 31, and the unlatching is effected by a rise 35 on a cam 36. The cam 36 is mounted on a shaft 37 and is adjustable thereon. The shaft 37 is driven through gearing 38 and 39 from the shaft of the shear roll 6, and therefore moves in timed relation with the shear. The control for the shear motor is of such type that it always stops with the blades in a determined position, so that when the shear is started up it will always cut a crop of the right length. Since the cam 36 is adjustable on the shaft 37, the rise 35 of the cam may be set so as to trip the latch at the exact moment desired in relation to the cutting action of the blades 8, to insure that the switch 12 will be moved downwardly at the proper moment. When 70 the cam rise 35 passes under the roller 40 on

an arm of the latch 32, the latch is tripped and the switch moves downwardly.

Resetting of the switch is effected by a setting motor 41 connected through gearing 42 to a crank shaft 43. A link 44 extends upwardly 5 from this shaft and has at its upper end an elongated opening 45 engaging a pin 46 on a lever arm 47 secured to the shaft 22. The control mechanism for the motor 41 is so arranged that the crank shaft 43 always stops with the 10 crank arm 48 in its uppermost position. When the crank shaft 43 is rotated, the shaft 22 is forced to rotate counter-clockwise, thus resetting the latch. The crank shaft 43 makes a 15 complete rotation, the opening 45 permitting of upward movement of the link 44 despite the fact that the pin 46 stays in the lower position because of the latching up of the trip lever 31.

In operation the switch 12 will first be in its uppermost position and the shear will be at rest. 20 Then when the flag switch 11 is actuated by an oncoming strip, the shear motor will start up and crop the leading end. This leading end passes beneath the switch 12. Then at the proper moment the latch is tripped and the switch 12 is 25 forcibly and quickly thrown to its lowered position so that the main body of the strip passes thereover to the run-out table 5.

The apparatus may be used for cropping the rear end of a strip and diverting this crop from 30 the run-out table. This is done by moving the switch 12 at an appropriate time just before the trailing end is cropped off. The setting and re-setting of the switch 12 is accomplished by the 35 operation of the motor 41 and the crank 43. The control of the motor is effected by electrical means, well known in the art, including a switch which limits the number of revolutions made by the motor, thus causing a limited and definite movement of the crank 43. In addition, adjustable time relays are provided one for the leading 40 end of the strip and one for the trailing end. These relays, which are well known per se, start the shear and re-set the motor at the proper time for disposing of the front and rear crop ends. 45 Of course, if it is desired, the second time-relay may be disregarded where front-end cropping only is desired.

I have illustrated and described a present preferred embodiment of my invention, but it will 50 be understood that this is by way of illustration only and that it may be otherwise embodied or practiced within the scope of the following claims.

I claim:

1. Apparatus for shearing comprising a shear 55 adapted to crop the leading end of an oncoming length of metal, a support for the metal on the delivery side of the shear, movable means for diverting the cropped leading end of the metal out of the horizontal plane of said support, and means for moving the diverting means into or out of position to divert the cropped end.

2. Apparatus for shearing comprising a shear 65 adapted to crop the leading end of an oncoming length of metal, and a support for the metal on the delivery side of the shear, the support having a vertically movable section arranged, when in one position, to divert the cropped end of the metal out of the general plane of the support, and when in another position to permit passage 70 of the metal over such support.

3. Apparatus for shearing comprising a shear adapted to crop the leading end of an oncoming length of metal strip, means for supporting the strip in a generally horizontal plane, and a switch 75

on the delivery side of the shear, the switch being vertically movable and arranged, when in one position, to divert the cropped end of the strip out of said plane, and when in another position 5 to permit passage of the metal therein.

4. Apparatus for shearing comprising a shear adapted to crop the leading end of an oncoming length of metal, a switch on the delivery side of the shear for diverting the cropped end of the metal 10 from its normal course, and means actuated by the movement of the metal toward the shear for actuating the switch.

5. Apparatus for shearing comprising a shear adapted to crop the leading end of an oncoming 15 length of metal, a switch for diverting the cropped leading end from the normal course taken by the metal, the switch lying on the delivery side of the shear, drive means for the shear, means for actuating the drive means in accordance with the 20 movement of metal toward the shear, and means operatively connected with the shear for actuating the switch.

6. Apparatus for shearing comprising a shear adapted to crop the leading end of an oncoming 25 length of metal, a switch lying on the delivery side of the shear and movable to either of two positions, the switch being effective in one position for guiding the metal into one path and in another position for guiding the metal into 30 another path, means biasing the switch toward one such position, means for holding the switch in the other position, and means for tripping the holding means.

7. Apparatus for shearing comprising a shear 35 adapted to crop the leading end of an oncoming length of metal, a switch lying on the delivery side of the shear and movable to either of two positions, the switch being effective in one 40 position for guiding the metal into one path and in another position for guiding the metal into another path, means biasing the switch toward one such position, means for holding the switch in the other position, and means operatively connected with the shear for tripping the holding 45 means.

8. Apparatus for shearing comprising a shear adapted to crop the leading end of an oncoming 50 length of metal, a switch lying on the delivery side of the shear and movable to either of two positions, the switch being effective in one position for guiding the metal into one path

and in another position for guiding the metal into another path, means biasing the switch toward one such position, means for holding the switch in the other position, means for tripping the holding means, and means for resetting the 5 switch in the holding position.

9. Apparatus for shearing comprising a shear adapted to crop the leading end of an oncoming 10 length of metal, a switch on the delivery side of the shear adapted to divert the cropped leading end from the path normally taken by metal passing through the shear, and power means constantly urging the switch into one position.

10. Apparatus for shearing comprising a shear 15 adapted to crop the leading end of an oncoming length of metal, a switch on the delivery side of the shear adapted to divert the cropped leading end from the path normally taken by metal passing through the shear, power means 20 constantly urging the switch into one position, a latch for holding the switch against the influence of said power means, and means connected with the shear for operating the latch.

11. Apparatus for shearing comprising a shear 25 adapted to crop the leading end of an oncoming length of metal, a switch on the delivery side of the shear adapted to divert the cropped leading end from the path normally taken by metal passing through the shear, power means 30 constantly urging the switch into one position, a latch for holding the switch against the influence of said power means, and means connected with the shear for operating the latch, said connection being adjustable so as to vary 35 the time relation between the tripping of the latch and a cut effected by the shear.

12. Apparatus for shearing comprising a shear adapted to crop the leading end of an oncoming 40 length of metal, a switch on the delivery side of the shear adapted to divert the cropped leading end of the metal from the path normally taken by metal passing through the shear, means operatively connected with the shear for controlling the movement of the switch from one 45 position to another, means for driving the shear, said means being effective for starting up the shear from rest, and means controlled by the movement of metal toward the shear for controlling the shear driving means.
